[57] CLAIM

The ornamental design for a rolling swivel handgrip massager, as shown and described.

DESCRIPTION

FIG. 1 is an isometric view of a massager in accordance with the present invention;

FIG. 2 is a top plan view of the massager of FIG. 1;

FIG. 3 is a bottom plan view of the massager of FIG. 1;

FIG. 4 is a left side elevational view of the massager of FIG. 1;

FIG. 5 is a right side elevational view of the massager of FIG. 1;

FIG. 6 is a front side elevational view of the massager of FIG. 1;

FIG. 7 is a rear side elevational view of the massager of FIG. 1;

FIG. 8 is a top plan view of the massager of FIG. 1 with the handle means rotated 90°;

FIG. 9 is a bottom plan view of the massager of FIG. 1 with the handle means rotated 90°;

FIG. 10 is a left side elevational view of the massager of FIG. 1 with the handle means rotated 90°;

FIG. 11 is a right side elevational view of the massager of FIG. 1 with the handle means rotated 90°;

FIG. 12 is a front elevational view of the massager of FIG. 1 with the handle means rotated 90°; and,

FIG. 13 is a rear elevational view of the massager of FIG. 1 with the handle means rotated 90°.
